UNITED STATES PATENT OFFICE.

PETER A. SOLEM, OF CINCINNATI, OHIO, ASSIGNOR TO J. A. FAY & EGAN COMPANY, OF CINCINNATI, OHIO, A CORPORATION OF WEST VIRGINIA.

GRINDING-MACHINE.

1,016,585.

Specification of Letters Patent.

Patented Feb. 6, 1912.

Application filed June 9, 1910. Serial No. 566,126.

To all whom it may concern:

Be it known that I, PETER A. SOLEM, a citizen of the United States, residing at Cincinnati, in the county of Hamilton and State of Ohio, have invented certain new and useful Improvements in Grinding-Machines, of which the following is a specification.

My invention relates to grinding machines for grinding or sharpening knives used in connection with wood working machinery, and it consists principally of an adjustable knife holding bar arranged to accommodate either regular slotted knives, or what is known as high speed knives which consist of plain thin strips of steel.

It is a well known fact that planer knives never have an absolutely true surface and that on this account it is impossible to set a knife on a machine twice in exactly the same relative position. If, therefore, when a knife is ground on one side it is reset on the work support for grinding the opposite side, the second bevel will not be exactly parallel to the first and the cutting edge will not be an absolutely straight line. This difficulty is overcome and much time saved by grinding both sides of the knife without changing its position on the work support.

The object of my invention is to provide a machine with a single grinding wheel and a knife holding bar arranged to accommodate either slotted or high speed knives, and in mounting the knife holding bar on the reciprocating carriage so that it may be adjusted into positions for grinding a knife from either one or both sides without changing its position on the knife holding bar.

The invention will be readily understood from the following description and claims, and from the drawings in which latter:

Figure 1 is a front elevation of my improved machine. Fig. 2 is a left hand side elevation of the same with the knife holding edge of the knife holding bar adjusted above the plane of its axis. Fig. 3 is a rear elevation of the machine. Fig. 4 is a right hand side elevation with the knife holding edge of the knife holding bar adjusted below the plane of its axis. In this view the side of the machine is partly broken away for better illustration. Fig. 5 is a plan view of the knife holding bar and carriage. Fig. 6 is a cross section of the knife holding bar on line 22 of Fig. 5. Fig.

7 is a sectional view of the feeding mechanism for the grinding wheel. Figs. 8 and 9 are details of an automatic belt shifting device. Fig. 10 is a cross section of a knife ground with a bevel from each face of the knife to the cutting edge thereof.

1 represents the main frame of the machine on which is mounted the reciprocating grinding head 2, in ways 3 3 having upwardly extending arms 4 and 5, in which is journaled the mandrel 6, fast upon one end of which outside of the arm 5 is the grinding wheel 7. Tightly secured on the opposite end of the mandrel 6 is the pulley 8 which carries a belt from the pulley 9, which is tight on the main feed shaft 10 which is journaled in suitable bearings in the lower part of the main frame 1.

11 is a pulley loosely mounted on the main feed shaft 10. The machine is driven by a belt operating on the pulleys 9 and 11, said belt being controlled by the shifter 12, having arms 13 and 14. The shifter 12 is actuated by means of the lever 15 fulcrumed in the lug 16 on the main frame 1.

17 is a carriage support mounted on the main frame 1 and rigidly secured thereto by any suitable means as by bolts 18.

19 is a reciprocating carriage sliding on ways 20 and 21 on the carriage support 17. Pivotally mounted in the carriage 19 is a knife holding bar 22 provided at either end with segments 23 having therein segment slots 24.

25 represents bolts passing through holes 26 in the end of the carriage and through slots 24. By loosening the bolts 25 the knife holding bar may be adjusted with its knife holding edge either above or below the plane of its axis for grinding a bevel from either face of the knife, after which the bolt 25 may be again tightened and the bar thereby rigidly secured in its adjusted position.

The knife holding bar 22 is provided with clamp sections 28 for clamping the knife on the knife holding bar 22. The clamps completely cover the knife holding face of the bar and protect the face of the bar and the knife from the water and particles of grit thrown off by the grinding wheel. The knife to be ground is placed on the face of the bar 22 and is clamped into position by the clamps 28 as shown in Fig. 6.

29 is a bolt passing through the clamp sec-

tions 28 and into the knife holding bar 22 by means of which the sections may be securely clamped against the knife.

30 is a set screw passing through the rear end of the clamp sections 28 taking against the face of the bar 22. The set screw 30 is provided for holding the rear end of the clamp sections 28 in the same relative plane as the forward end which is in contact with 10 the knife.

31 is a shaft journaled in suitable bearings on which is secured the worm 32 engaging the worm wheel 33, on the vertical shaft 34, on which is a pinion 35, engaging the 15 rack 36 on the reciprocating carriage 19. I provide a cover for the worm and worm wheel which is partly broken away in the views I have shown for better illustration.

37, 38 and 39 are pulleys on the shaft 31, 20 37 and 39 being loosely mounted thereon and 38 being secured to the shaft.

40 is a pulley secured on the mandrel 6 between the arms 4 and 5 and is connected with pulleys 37, 38 and 39 by means of a 25 crossed belt 41 and an open belt 42. When the belts are shifted toward the left side of the machine so that the crossed belt 41 is running on the pulley 38, the pulley 38 is revolved toward the rear of the machine 30 and motion is imparted to the worm 32, worm wheel 33, shaft 34 and pinion 35 and the carriage 19 is driven to the left; when the carriage 19 reaches the limit of its travel to the left, the belts 41 and 42 are automatically shifted to the right so that the belt 35 42 runs on the pulley 38, revolving it toward the front of the machine and causing the carriage 19 to travel to the right. When the carriage 19 reaches the limit of its travel 40 to the right the belts 41 and 42 are again automatically shifted and the direction of the travel of the carriage is again reversed.

43 and 44 are dogs adjustable in the slot 45 in the reciprocating carriage 19. The 45 dogs 43 and 44 are secured in position by means of hand nuts 46 threaded on the bolts 47 the heads 48 of which fit into the slot 45.

49 is a lever secured on the forward end of the shaft 50. The forward end of the 50 shaft 50 is journaled through the front part of the main frame 1 and the rear end is supported by the lug 51. The shaft 50 has an arm 52 which is connected with the shifter 53 having members 54 and 55 for controlling 55 the belts 41 and 42.

56 is a finger pivoted in the lever 49 and projecting inwardly toward the carriage support.

Normally the shifter 53 is in position as 60 shown in Fig. 3 with the belts running on the loose pulleys 37 and 39 and the lever 49 in a vertical position. Just before the carriage 19 reaches the limit of its travel to the right the dog 43 engages the finger 56 and 65 the upper part of the lever 49 is pushed

slightly to the right of a vertical position. The movement of the lever rocks the shaft 50 which, in connection with the automatic shifting device hereinafter described, moves the shifter 53 a sufficient distance to the left 70 of its normal position to cause the belt 41 to run on the pulley 38 and the belt 42 to run on the pulley 39 thereby reversing the direction of travel of the carriage 19. Just before the carriage 19 reaches the limit of its travel to the left the dog 44 engages the finger 56 and the upper end of the lever 49 is pushed slightly to the left of a vertical position again rocking the shaft 50 which, in connection with the automatic shifting device hereinafter described, moves the shifter 53 a sufficient distance to the right of its 80 normal position to cause the belt 42 to run on the pulley 38 and the belt 41 on the pulley 37, again reversing the direction of the 85 travel of the carriage 19.

To adjust the knife holding bar 22, the carriage 19 should be brought to a stop with the knife holding bar at the left of the grinding wheel. This is readily accomplished by raising the finger 56 and allowing the dog 44 to pass. The lever 49 is then shifted by hand to its normal or vertical position and the carriage will stop. The knife holding bar can then be easily adjusted to any desired angle. After the bar is 90 adjusted to the desired position the lever is shifted to the left, the finger 56 is again raised allowing the dog 44 to pass to the right after which it is allowed to drop back 100 to its normal position so that it will engage the dogs 43 and 44 with each movement of the carriage to the right or to the left. The lever 49 is provided with a suitable handle 58.

In order to shift the belts 41 and 42 to the proper positions, it is necessary to move the shifter 53 farther to the right or left of its normal position than it is moved by the dogs 43 and 44. To accomplish this I 110 provide on the shaft 50, an arm 59 which is secured to the shaft by any suitable means as by pin 60. Pivoted to one end of said arm on pivot 61, is an intermediate arm 62.

63 is a rod or bolt pivoted to the main 115 frame of the machine on pivot 64 and taking through one end 65 of the intermediate arm 62, and which may be provided at its end with a stop as the nuts 66.

67 is a spring engaging the head 68 of 120 the rod or bolt 63 and the shoulder 69 of the intermediate arm.

By shifting the upper end of the lever 49 slightly to the right of a vertical position the lower end of the arm 59 is moved to 125 a point slightly to the left of the line A A and the spring 67 is then compressed. The pressure of the spring 67 forces the intermediate arm 62 upward on the rod or bolt 63 which upward movement carries the 130

lower end of the arm 59 still farther to the left of the line *a a* thus rocking the shaft 50 and moving the shifter 53 the required distance to the left. By shifting the upper 5 end of the lever 49 slightly to the left of a vertical position the lower end of the arm 59 is moved to a point slightly to the right of the line *A A* and the spring 67 is again compressed. The pressure of the spring 67 10 against the intermediate arm 62 again forces the arm upward on the rod or bolt 63 thus moving the lower end of the arm 59 farther to the right of the line *A A* rocking the shaft 50 and moving the shifter 53 the 15 required distance to the right. This operation is repeated with each movement of the carriage to the right or to the left.

70 is a feed wheel journaled on the feed screw 71 threaded in the nut 72 which is 20 secured to the grinding head 2.

73 is a double arm loosely mounted on the feed screw 71 and has pivoted to its lower end on pivot 74 one end of a link 75. The opposite end of the link 75 is connected 25 with the lever 49 and is adjustable vertically of said lever in the slot 76 and is secured in position by means of a hand nut 77 threaded on the bolt 78 the head of which is fitted into the slot 76.

30 79 is a pawl pivoted to the arm 73 on pivot 80 and which engages the teeth 81 in the face of the feed wheel 70. The feed wheel 70 has a recess 82 in which is an annular groove, 83.

35 84 is an apron fitting into the recess, covering the groove, and extending over the face of the feed wheel 70.

85 is a bolt with a wedge shaped head 86 having threaded on its outer end a hand 40 nut 87. The bolt is held in position in the groove by the lug 88. By tightening the hand nut 87 the apron is firmly secured in position.

The distance which the feed wheel is 45 revolved by each movement of the pawl 79 is determined by the position of the link 75 on the lever 49. By adjusting the link 75 downwardly on the lever the distance which the feed wheel 70 will be revolved by each 50 movement of the pawl 79 is increased. By adjusting the link 75 upwardly on the lever the distance which the feed wheel 70 will be revolved by each movement of the pawl 79 is decreased.

55 The grinding wheel 7 is fed toward the work by means of the feed wheel 70 and the feed screw 71. When the dog 43 pushes the lever 49 to the right, the pawl 79 by means of the link 75 and the double arm 60 73 is also moved to the right. When the dog 44 pushes the lever 49 to the left the pawl is also moved to the left and it being then in engagement with the teeth 81 in the feed wheel, the feed wheel is revolved a 65 corresponding distance and the grinding

wheel is fed toward the work. This operation is continued until the apron 84 is interposed between the pawl 79 and the teeth 81 when the feed automatically ceases.

The feed wheel 70 is provided with a 70 scale by which the apron 84 may be set so that it will be interposed between the pawl 79 and the teeth 81 for stopping the feed at a predetermined point. The wheel 70 is also provided with a handle 89 so that it 75 may be turned by hand when desired.

90 is a cover for the grinding wheel which is rigidly secured to the main frame 1 by any suitable means. One side of the lever 91 is removable so as to permit of easy access to the grinding wheel 7. For holding the removable side 91 of the cover in position, I provide a groove in its lower edge which fits over the stationary part of the cover, and a bolt 92 pivoted on a pivot 93 80 85 on the top of the cover 90 and arranged to pass through the slot 94 in the removable side 91 of the cover, said bolt having threaded on its outer end a hand nut 95 which fits against the removable side 91 of 90 the cover and holds it firmly in position. To remove the part 91 of the cover, the hand nut 95 is loosened and the bolt 92 raised on its pivot until it is clear of the slot when the removable side 91 of the cover 95 may be lifted from its position. I also provide openings 96 in the cover to allow of the movement backward and forward of the grinding wheel on its mandrel within said cover.

97 is a reservoir cast in the frame of the machine immediately under the grinding wheel 7.

98 is a centrifugal pump into which the water passes from the reservoir 97 from 105 which it passes into the hose 99 which carries it over the cover 90 to the opening 100 from which it is discharged onto the grinding wheel 7. The water is then caught in the trough 101 in the reciprocating carriage 110 19 from which it passes through the opening 102 into the trough 103 in the carriage support 17, thence through the opening 104 into the reservoir 97.

105 is a stop cock for controlling the flow 115 of the water.

The pump 98 is driven by means of a pulley 106 supported in bracket 107 which receives the belt 108 from the pulley 109 secured on the main feed shaft 10 in the 120 frame of the machine.

The operation of my improved machine may be briefly described as follows: The knife to be ground is first clamped onto the knife holding bar 22 and the bar is then 125 adjusted in position with its knife holding edge above or below the plane of its axis according to the bevel to be ground on the knife. The operator then moves the grinding wheel 7 up to the knife and adjusts the 130

apron 84 on the feed wheel 76 for stopping the feed at the desired point. The machine is then set in motion and the grinding wheel is caused to revolve in the direction of the arrow in Fig. 4. The crossed and open belts 41 and 42 cause the rotation of the shaft 31 which latter, by means of the worm and worm wheel and the rack and pinion causes the carriage to reciprocate in front of the grinding wheel. Just before the carriage reaches the limit of its travel to the right, the dog 43 engages the finger 56 and the upper part of the lever 49 and the pawl 79 are moved to the right and the direction of the travel of the carriage is reversed. The carriage then travels to the left until the dog 44 engages the finger 56 and the upper part of the lever 49 and the pawl 79 are moved to the left and the pawl 79 being then in engagement with the teeth 81 revolves the feed wheel a distance corresponding to the movement of the pawl and the grinding wheel 7 is fed toward the work. The movement of the lever again reverses the direction of travel of the carriage. This operation is continued until the apron 84 is interposed between the pawl 79 and the teeth 81 when the feed is automatically stopped. A bevel may then be ground from the opposite face of the knife without changing its position on the knife holding bar by readjusting the knife holding bar according to the bevel desired and repeating the operation already described.

Having fully described my invention, what I claim and desire to secure by Letters Patent is:

1. In a knife grinding machine, the combination of a grinding wheel, a reciprocating carriage, a knife holding bar pivoted in the carriage and adjustable into positions for grinding the knife on both sides without resetting it on the knife holding bar.
2. In a grinding machine the combination of a grinding wheel, a reciprocating

carriage, a knife holding bar pivotally mounted in said carriage and adapted to hold either plain or slotted knives, means for clamping the knife on the knife holding bar, means for adjusting said bar so that the knife may be brought into position to be ground from either one or both sides without changing its position on the knife holding bar, substantially as described. 50 55

3. In a grinding machine the combination of a grinding wheel, a movable support therefor, a stationary cover for the wheel, a reciprocating carriage, a knife holding bar having a knife holding face 60 arranged adjacent to the grinding wheel and adapted to hold either plain or slotted knives, clamps covering the said knife holding face of said bar for clamping the knife, means for adjusting said bar so that the 65 knife may be brought into position to be ground on one or both sides without changing its position on the knife holding bar, substantially as described.

4. In a grinding machine the combination of a grinding wheel, a movable support therefor, a reciprocating carriage, a knife holding bar pivotally mounted in the carriage, a knife holding face arranged adjacent to the grinding wheel and adapted to 75 hold either plain or slotted knives, clamps covering said knife holding face for clamping the knife, means for adjusting said bar so that the knife may be ground from either 80 one or both sides without changing its position on said knife holding bar, means for automatically feeding the grinding wheel toward the knife and means for automatically stopping the feed at a predetermined point, substantially as described. 85

In testimony whereof, I have subscribed my name hereto in the presence of two subscribing witnesses.

PETER A. SOLEM.
